TORPEDO STEERING MECHANISM

Charles H. Tindal, State College, Pa., assignor to the United States of America as represented by the Secretary of the Navy

Filed May 8, 1947, Ser. No. 746,805

3 Claims. (Cl. 114—24)

This invention relates to guided missiles, such as torpedoes, and especially to the steering mechanism for such missiles wherein the position of a control surface or steering member for guiding the missile, e.g. the rudder, is governed either by a gyroscope or in accordance with acoustic signals emanating from a target.

By this invention there is provided a steering system for torpedoes wherein, initially after the torpedo is launched, the control surface is governed exclusively by a gyroscope for a predetermined period to maintain the torpedo traveling in a preassigned direction, for example, in the direction in which it is launched. After the torpedo has traveled some distance from the launching vessel, the steering system is then conditioned so that the position of the control surface may be transferred from gyroscopic influence to control by a signal translating system that is responsive to signals emanating from a target, such as propeller and ship noises, the said signal translating system being effective to so position the control surface as to guide the torpedo to the target.

The signal translating system per se while forming no part of the present invention may comprise, for example, a pair of hydrophones sensitive to compressional waves, or acoustical vibrations within a predetermined frequency range, mounted on the torpedo in a common horizontal plane but on opposite sides of the center line, so that the percentage difference in the intensities of the outputs of the two hydrophones is a measure of the bearing of the target relative to the torpedo. As later described in greater detail, the hydrophone outputs are amplified, rectified and applied to a comparison circuit, so that the comparison circuit output may be utilized for controlling the azimuthal position of the torpedo in accordance with the percentage difference in the intensities of the signal on the hydrophones.

The present invention in one important aspect deals with the simplification of the operative linkage between the gyroscope and the torpedo steering engine, a part of this operative linkage also being utilized to effect control in response to acoustic signals; and involves also the basic combination embraced in the idea of conditioning the torpedo steering system for control in response to both gyroscope and acoustic signals, only after a run of predetermined duration during which the torpedo steering system is exclusively under control of the gyroscope.

The importance of this concept of this invention will be appreciated once it is considered that at the beginning of the run, whether the torpedo is launched from an airplane or from a submarine, the noise level created by the launching is inevitably very much higher than normal running noise of the torpedo. Moreover, electronic devices employed in the steering system, and operating by virtue of thermionic emission of electrons require time to attain their optimum operating temperature. For these and other reasons that will be apparent later, this invention provides means for maintaining the torpedo under exclusive gyroscopic control at the start of the

run; and at a predetermined time thereafter conditioning the steering system for transfer to acoustic response.

It should be understood that under the provisions of this invention no immediate transfer to acoustic response is effected, that is, the torpedo continues to run under gyroscope control until it reaches a point in its path where the target signal level at the hydrophones is of at least a preassigned magnitude. This transfer as determined by the magnitude of signal level entails inherently a restriction of the range at which the rudder may be connected to control in accordance with target signal. This follows from the fact that the transfer element must be set to allow for torpedo self noise and ambient submarine signals so that transfer can be effected only when the total signal level is somewhat above the target signal level for which the signal transmitting system is capable of controlling the rudder in accordance with signals received by the hydrophones in the presence of self noise and ambient submarine signals. This is achieved, for example, by providing a suitable relay in the output circuit of the amplifier for the signal received by the hydrophones. This relay is set to function whenever the noise level to which one or both of the hydrophones are subjected reaches a threshold value; that is, the energizing circuit for this relay may be connected to the amplified output of one hydrophone, or to the amplified output of the differential signal level.

In accordance with another feature of the present invention means are provided for preventing return to gyroscope control once the noise level reaches the aforesaid threshold value. This feature of the invention is achieved by providing a hold-down relay and permits re-attack by the torpedo in the event of an initial miss of the target. For example, if the torpedo should miss the target on the initial run it will commence to circle either to the right or left, depending upon the direction in which the rudders were displaced by the last received signal, and will continue to circle until it again picks up the target noise. This action for re-attack would not be effected if gyroscope control were re-established upon reduction of available acoustic level.

It has been the practice prior to this invention to utilize mechanical linkages entirely, between the gyroscope and the control valve of the azimuth steering engine. The present invention has simplified this mechanical linkage by incorporating a suitable electro-magnetic means for actuating the control valve of the steering engine, and selectively energizing the said electro-magnetic means in response to a coarse restoring force initiated by the gyroscope of the torpedo. This has been particularly advantageous in adapting the torpedo to acoustic control since the same electro-magnetic component may be utilized also to actuate the steering engine in response to acoustic signals.

It is apparent from the foregoing, therefore, that it is a primary object of this invention to simplify the operating linkage between the gyroscope of a torpedo and its azimuth steering engine.

It is also an object of the invention to provide a steering system wherein control may be subject to response to acoustic signals as well as gyroscopic action.

Another object of the invention is to provide means responsive to a predetermined acoustic level for effecting a non-reversible transfer of torpedo steering control from gyroscopic response to acoustic response.

It is a still further object of this invention to provide an enabling device which, after a predetermined run of the torpedo, will condition the steering system there-of so that transfer from gyroscopic control to acoustic control may be effected when the torpedo is subjected to a signal of predetermined intensity. Prior to actua-

tion of the enabling device the torpedo is exclusively under gyroscopic steering control.

Other objects and advantages of this invention will be apparent from the following description of a preferred embodiment of the invention illustrated in the accompanying drawings, wherein

Fig. 1 is a plan view in perspective of the gyroscope assembly, showing the enabling device and the electro-magnetic means for actuating the steering engine in response to the course restoring force of the gyroscope;

Fig. 2 is an elevational view in cross-section of the enabling device, the section being taken on lines 2-2 of Fig. 4;

Fig. 3 is a plan view in perspective showing the brackets for mounting the electro-magnetic means on the 15 gyroscope housing;

Fig. 4 is a plan view partly in cross-section of the assembly shown in Fig. 1, but including the steering engine;

Fig. 5 is a longitudinal elevational view of the electro-magnet and steering engine assembly, showing the electro-magnet in cross-section, the section being taken on lines 5-5 of Fig. 4;

Fig. 6 is a perspective elevational side view partly in cross-section showing the entire steering assembly;

Fig. 7 is a diagrammatic view illustrating the operation of the improved system for controlling the position of the steering member, e.g., rudder, in response to course restoring force of the gyroscope; and,

Fig. 8 is a schematic electrical circuit diagram showing the electrical connections involved in the steering system of this invention.

Referring now to the drawings and particularly to Figs. 1, 4, 6 and 7 the gyro-mechanism indicated generally at 10 in the drawings comprises the housing 11 in which the gyroscope (not shown) is contained and initially driven to its required spinning velocity by the tooth rotor 12. This housing is shown assembled on a large base plate 13 which is adapted for mounting in the torpedo without affecting adjustment of the individual mechanisms assembled thereon. The lower end of the gyroscope housing is secured to the base plate 13 and has its upper end closed by a suitable cover plate 14 of bronze, for example, on which is assembled the pallet mechanism indicated generally in the drawings at 15.

The pallet mechanism 15 comprises the means for utilizing the directive force of the gyroscope to selectively energize the electro-magnet indicated generally at 43. The main function of the pallet mechanism is to transmit movement from the gyroscope to the selective energizing means for the electro-magnet without setting up a disturbing torque that will cause the gyroscope to precess. This is accomplished by effecting an intermittent light contact of the small cam pawls 16 (Fig. 7) with the cam surface 17 of the cam plate 18 which is rigidly secured to the top of the outer gimbal ring (not shown) of the gyroscope. The cam pawls 16 are fitted and pinned to the pallet shaft 19 which is rotatably supported in a vertical bearing sleeve of a pallet holder, the sides of which are machined with a sliding fit for insertion in the pallet slide 20. The pallet which comprises the blade 21 extends from a hub 22 that is drilled to fit over the upper end of the shaft 19 to be there clamped in place. The slide 20 is shown in the form of a T-shaped member having a channel 23 machined on its upper side for receiving the pallet holder. A large hole 24 is drilled through the slide for insertion of the bearing sleeve of the holder with sufficient clearance to permit limited adjustment of the pallet holder in the slide. The bottom and sides of the slide 20 are machined to a sliding fit in the channel 25 of the top cover plate 14, so that T end of the slide bears against the cam surface 26 formed on the bevel gear 27. The cam surface 26 and bevel gear 27 are rotatably mounted on the stud shaft 29 and driven by the torpedo propeller shaft through the

bevel gear 28 to impart a reciprocating motion to the slide 20 and pallet blade 21. Although not shown in the drawings the slide 20 is biased toward the cam surface 26 by means of a pair of springs each one of which presses (the pressing is done through plungers which barely show in Fig. 4), against the projecting surface of the T.

The slide 20 is retained in the channel 25 of the top cover plate by means of the slide cover 30 which is 10 suitably machined to fit over the pallet slide. This cover is provided with two posts 31 and 32 which serve as pivots for the pallet pawls 33 and 34. These pawls are cross-connected by the switch operating bar 35 which is shown secured by means of screws to the adjusting links 36 and 37 which are attached to the pawl arms 33 and 34 by suitable pins fitted to the ends of each of the pallet pawls.

The switch bar 35 is shown provided with an offset portion 38 positioned between the operating buttons 41 and 42 of their respective micro-switches 39 and 40 which are mounted on the top plate 14 so as to face each other. Thus it will be seen that when the cam 26 is in a position to permit the pawl 16 to be moved toward the gyro cam plate 18 by the spring loading applied 25 to the pallet slide 20, and the torpedo course differs on either side of the proper course or reference axis of the gyro, one of the pawls will have moved into line with and will contact the cam surface 17, imparting a slight rotary movement to the pallet shaft 19 with a consequent angular displacement of the pallet blade 21. Upon further rotation of the cam 26 the slide 20 will be advanced on the top cover plate to move the pawls 16 away from the gyroscope cam 18 and to move the pallet blade 21 into contact with one of the pawls 33 or 34 35 which through the connecting linkage with the switch operating bar 35 will operate one or the other of the micro-switches 39 or 40 to energize either end of the double solenoid electro-magnet 43. It is to be observed that movement of the pawl 16 toward the gyro cam 18 when the course of the torpedo coincides with the gyro axis will cause the pawls to straddle the cam surface 17, in which position the pallet blade 21, when moved by the cam 26 to a position away from the gyro 40 scope cam plate will pass between the pallet pawls 33 and 34.

The electro-magnet 43 is attached to the base plate 13 by means of the bracket 44 and as shown in Fig. 5 comprises a pair of axially aligned and differentially operated solenoids 45 and 46, each being wound about their respective cores 47 and 48 and encased within a metal sheath 49. The axial length of each core is less than the axial length of its respective solenoid to provide a space within the central portion of the electro-magnet for supporting an armature 50 so that it is free to move in either 55 of two directions, to close the air gap between it and a respective one of the cores, the direction of the movement being dependent upon which of the coils is energized by its respective energizing circuit coincident with the operation of the micro-switches. An arm 51 is rigidly screwed to the armature and transmits its movement through the linkage 52 to the forked end 53 of the steering engine valve stem 54.

As shown in Fig. 6 the steering engine 55 is attached to the right hand side of the gyroscope housing 11 with 60 two holding screws, the recess 56 (see Fig. 1 being machined in the walls of the steering engine block 57 to fit the rectangular lug 58' extending from the gyroscope housing. The engine block 57 has a cylindrical bore 58 machined therein for the insertion and movement therein of the piston 59. The piston 59 and rod 60 (see Fig. 5) are shown machined of one piece, with an end of the rod 60 protruding through a stuffing box 61 and gland 62 in threaded engagement with the forked connection 63 for connection to the steering rod 64 (see 65 Fig. 6). The rod 64 in turn is connected with the ver-

tical steering rudders 64a (Figs. 6 and 7), which rudders are an exemplification of the control surface herein contemplated.

The piston 59 is operated by the admission of air under pressure at either side thereof, the flow of said air being governed by a valve 65 comprising a sleeve 66 and cooperating valve stem 54. The sleeve 66 is fitted into a hole 67 that is drilled into the engine block parallel with and below the engine cylinder to provide a valve chamber having the necessary annular grooves, valve seats and ports for air entry and exhaust as is clearly shown in Fig. 7. The valve stem is shown in Figs. 5 and 7 machined with three grooves, the center groove 68 controls the flow of air into the cylinder; and the outer grooves 69 and 69' direct the flow of exhaust air.

Referring again to Fig. 7 it will be noted that air is furnished through the valve casing into the central groove 70 machined in the sleeve 66. Holes 71 are drilled through the sleeve extending from the bottom of the groove to permit air to pass to the central groove 68 of the valve 65 and thence upon displacement of the valve in either direction into the working end of the cylinder 58 through openings 72—73, or 74—75, drilled in the sleeve, and their respective communicating grooves 76 and 77.

It is thus apparent that the steering engine 55 is operated from the pallet pawls 33 and 34 electrically in response to a course correcting force from the gyroscope. However, in accordance with a principal object of this invention and as illustrated in Fig. 8, provision is made to substitute, at a predetermined acoustic signal level, an acoustic-control for the gyro-control described above, it being apparent from the wiring diagram of Fig. 8 that the solenoids 45 and 46 are selectively energized by the acoustic signal system to control the steering engine.

The particular acoustic signal system for selectively energizing the solenoids is not a part of the present invention and is disclosed only diagrammatically, it being clearly understood however that there are a number of such systems known to the art capable of achieving this purpose, and readily adaptable to the combination herein described.

There is also shown diagrammatically in Fig. 8 at 78 an enabler switch (indicated diagrammatically in Fig. 8 by the single pole double throw switch) which maintains the solenoids 45 and 46 exclusively under control of the gyroscope for a predetermined run of the torpedo. While any number of devices known to the prior art may be utilized to delay conditioning of the operating circuit for transfer from gyroscope to acoustic response, one highly successful device is illustrated in Figs. 1, 2, 4, and 6, and designated generally by reference numeral 78. This device comprises a locking type of micro switch 80 adapted to be operated by the cam 81. The mechanism (see Fig. 1) for driving this cam includes a shaft 82 which is driven by the bevel gear 83, which gear in turn meshes with the cam bevel gear 27, and which carries the worm 84. This worm drives the wheel 85 and through an additional worm and wheel reduction 86—87 (see Fig. 4) drives the cam 81. The surface of the cam upon a predetermined rotation bears against the operating button 88 moving the switch arm into a position of locking engagement with the contact 89 to condition the circuit for transfer from gyroscope to acoustic control. In the displaced position the switch arm can be returned only manually by the reset button shown at 90 in Fig. 2.

Referring again to Fig. 8 it will be observed that after the enabler switch 78 is displaced from the position shown to close the circuit leading from contact 89 the solenoids 45 and 46 may be energized by the circuit controlled by the gyroscope-actuated micro switches 39 and 40 (indicated diagrammatically at 79) or by the acoustic signal system operating the relay indicated at 91, dependent upon the condition of the relay 92 which determines

whether the gyro-actuated microswitch arrangement 79 or the swinger contact of relay 91 will be connected in circuit to operate the solenoids 45, 46. It should be noted that energization of the relay 92 is controlled by the relay 96 which in turn is controlled by a suitable signal intensity responsive circuit, so that the relay 92 becomes energized only when an acoustic signal of predetermined level and duration is received by the hydrophones. Thereafter the relay 92 is mechanically locked in thrown position as by a catch 93 so that it cannot return to the position shown which would permit a return to gyroscope control. It should further be noted that when relay 92 has become energized, the swinger contact of relay 91 completes the circuit to either solenoid 45 or 46, dependent upon the character of the signal applied to the D.C. amplifier, thus effecting torpedo steering either to port or to starboard dependent upon the relative direction of the target which gives rise to the signal as received by the R and L (right and left) hydrophones.

20 In the illustrated signal translating system, the input circuit to the A.C. amplifier and automatic volume control is through the commutator switch so that the pre-amplified output signal from one hydrophone and then the other serves as the input. The rectified D.C. outputs 25 are alternately applied, by means of the second commutator switch and in accordance with conventional technique, to the condensers 94 and 95 shunted by bleeder resistances 97 and 98 and connected in series opposition in a conventional signal comparison arrangement. Thus 30 each condenser is in turn energized for a short time in accordance with the amplified (D.C.) output of its respective hydrophone. Accordingly, the signal applied to the D.C. amplifier is in effect a measure of the percentage difference between intensities of the signals on 35 the two microphones.

While a particular and preferred embodiment of this invention has been disclosed it is understood that such disclosure is for the purpose of illustration only, and not for the purpose of limitation, reference for this 40 latter purpose being had to the appended claims.

I claim:

1. In combination with a propulsive torpedo: torpedo steering means including a pair of opposed solenoids and an energizing source for producing a torpedo turn in a 45 direction corresponding to selective energization of said solenoids; a course gyroscope and switches selectively actuated thereby in accordance with deviation of the torpedo from a predetermined course; first and second switch means; electro-acoustic means, including a pair 50 of hydrophones for sensing acoustic target signals, and operating said first switch means from a first condition to a second condition in accordance with the direction, relative to torpedo heading, of the target which gives rise to said acoustic target signals; said electro-acoustic 55 means further operating said second switch means from a first condition to a second condition in response to sensing an acoustic target signal exceeding a predetermined threshold amplitude; an enabler switch; initial run control means for operating said enabler switch from 60 a first condition to a second condition after expiration of a predetermined torpedo run interval; said enabler switch in its first condition connecting the energizing source and solenoids of said steering means in circuit with said gyro-actuated switches for exclusive control 65 thereby until expiration of said predetermined interval; said enabler switch in its second condition connecting the solenoids through said second switch means in the first condition thereof, before operation of said second switch means in response to an acoustic target signal exceeding said threshold amplitude, to continue control of said torpedo steering means by said gyro-actuated switches until operation of said second switch means to its second condition; and means for thereafter holding 70 said second switch means in its second condition, said 75 second switch means then connecting the solenoids in

circuit with the first switch means for exclusive control thereby to effect torpedo steering in accordance with operation of said first switch means to its first and second conditions by said electro-acoustic means.

2. A combination as defined in claim 1, including a pair of serially-connected capacitors, wherein said electro-acoustic means provides a pair of D.C. signals having amplitudes differing in accordance with the sense and extent of target direction deviation from torpedo heading, and applies said D.C. signals individually to said capacitors to provide a summation signal across said pair of capacitors corresponding in polarity and magnitude to the sense and extent of said target direction deviation, and means utilizing said summation signal for actuation of said first switch means.

3. In combination with a propulsive torpedo: torpedo steering means; course gyroscope means for controlling said torpedo steering means in accordance with deviation of said torpedo from a predetermined course; electro-acoustic means for sensing acoustic target signals and for controlling said torpedo steering means in accordance with the direction, relative to torpedo heading, of the target which gives rise to said acoustic target signals; intensity switch means; said electro-acoustic means further operating said intensity switch means from a first condition to a second condition in response to sensing an acoustic target signal exceeding a predetermined threshold amplitude; an enabler switch; initial run

control means for operating said enabler switch from a first condition to a second condition after expiration of a predetermined torpedo run interval; said enabler switch in its first condition connecting said torpedo steering means in circuit with said course gyro means for exclusive control thereby until expiration of said predetermined interval; said enabler switch in its second condition connecting said torpedo steering means in circuit with said course gyro means, through said intensity switch means in its first condition to continue control by said course gyro means until operation of said intensity switch means to its second condition in response to an acoustic target signal exceeding said threshold amplitude; and means for thereafter holding said intensity switch means in its second condition, said intensity switch means then connecting said torpedo steering means in circuit with said electro-acoustic means for exclusive control thereby.
